UNITED STATES PATENT OFFICE.

WILLIS A. WHIPPLE, OF CHICAGO, ILLINOIS, ASSIGNOR TO BLEADON-DUN COMPANY, OF CHICAGO, ILLINOIS, A CORPORATION OF ILLINOIS.

SOLDERING IRON.

Application filed June 14, 1923. Serial No. 645,241.

To all whom it may concern:

Be it known that I, WILLIS A. WHIPPLE, a citizen of the United States, and a resident of Chicago, in the county of Cook and State 5 of Illinois, have invented certain new and useful Improvements in Soldering Irons, of which the following is a specification.

This invention relates to improvements in electrically heated soldering irons and has 10 for its principal object to produce an improved device of the class described which is simple and economical in construction and operation.

More specifically my invention contemplates the manufacture of a device of the class described by the process of forming, in combination with an electrical heating element, a sheet metal blank, to produce a finished article much cheaper than electric 20 devices heretofore have been produced for similar purposes.

The invention may best be understood by reference to the accompanying drawings illustrating one form in which it may be embodied.

In these drawings:

Figure 1 is a plan view of a soldering iron constructed in accordance with my invention.

Figure 2 is a sectional view taken on line 30 2-2 of Figure 1.

Figure 3 is a view of a sheet metal blank from which the main portion of the device is formed.

Figure 4 is a view of the blank in partially formed condition with portions broken away and showing a portion of the heating element in dotted lines.

Figure 5 is an enlarged detail view of the 40 end of the iron before the final pressing operation.

Figure 6 is a view similar to Figure 5 but after the final pressing operation.

The main elements of my improved soldering iron comprise a head 10, a shank 11 and 45 a handle 12. The electric heating device comprises a resistance element 13 which may be of any ordinary form including coils of resistance wire insulated by suitable means such as mica sheets. The resistance element 50 is preferably formed in a relatively flat section, as shown, to be fitted in the head 10 as it is finally formed, as will now be described.

The head 10 and shank 11 are preferably 55 formed of one piece of sheet metal. For this purpose a blank A is shaped substantial-

ly as shown in Figure 3, in which a portion 15 is provided to form the head 10, and the portion 16 is provided to form the shank 11. By forming operations of the usual kind, preferably by machinery, the side margins 17, 17 of portion 15 are turned upwardly and the side margins 18, 18 of portion 16 are also turned upwardly, substantially as shown in Figure 4. The central part of portion 16 may also be concaved to extend a short distance into the flat central part of portion 15 to form a shoulder, as shown. With the parts in this form, the resistance element 13 may be fitted in the head, which is of proper dimensions to receive said element between 70 the side margins 17, 17 thereof, but at a distance from the working point 20. The conductors 14, 14 of said resistance element are also inserted between the walls 18, 18 of shank 16. The walls 17, 17 are then 75 folded over the resistance element, with their margins meeting substantially on the center line. The walls 18, 18 of the shank are also closed together, preferably in a tubular form, as shown, with the conductors 14, 14, 80 extending therethrough. The folded walls 17, 17 at the extreme point of the head and beyond the heating element 13 are finally pressed against the lower wall, as shown in Figure 6, and finished along the edges by 85 grinding, if desired, to form a working point of substantial thickness, for the application of solder in the usual manner. The handle 12 may be of any suitable form and construction, as for example, it may comprise 90 a hollow piece of heat resisting material convenient in shape, with shank 11 fitted into one end and with conductors 14, 14 extending therethrough for connection with a source of current in the usual manner. 95

It will be understood by those skilled in the art that the operations necessary for forming the blank described are readily accomplished by machinery including suitable forming dies, and that the several operations may be performed singly, or more than one operation may be performed simultaneously, by means of compound dies, without departing from my invention. It will be further obvious that the shank 11 might 105 be shaped in hollow form before the heating element 13 is applied, in which case the conductors 14, 14 would be inserted through the shank.

A soldering iron constructed as above de- 110

scribed is especially suited for relatively light work. It can be produced in large quantities, being extremely simple and requiring a minimum of labor and material in its manufacture, so that its cost may be reduced far below that of the more complicated electric devices now in general use for a similar purpose.

I claim as my invention:

- 10 1. A soldering iron comprising an insulated electric heating element, a head and a shank, said head and shank being formed of a single piece of sheet metal folded over and enclosing said heating element within said head.
- 15 2. A soldering iron comprising a head and a shank formed of a blank of sheet metal folded laterally to form said head in double thickness, and an insulated electric heating element contained between the two thicknesses of metal.
- 20 3. A soldering iron comprising a head and shank formed of a blank of sheet metal, said head being folded in double thickness, and said shank being formed with a longitudinal passageway therethrough, an electric heating element in said head enclosed between the two thicknesses of metal, and provided with conductors passing through the passageway in said shank.
- 25 4. A soldering iron comprising a head and

shank formed of a blank of sheet metal, said head being folded laterally in double thicknesses with their forward margins pressed together to form a pointed working end, and an insulated electric heating element contained between the two thicknesses of metal rearwardly of said working end.

5. The method of forming the head and shank of a soldering iron from a single blank of sheet metal, which consists in folding a portion of said blank into a plurality of thicknesses to form a head, and forming another portion of said blank into a shank having its walls curved in cross section.

6. The method of forming the head and shank of a soldering iron, which consists in folding over the lateral margins of a sheet metal blank to form a plurality of thicknesses of metal in the head.

7. The method of making electric soldering irons, which comprises forming a head of double thicknesses of sheet metal, with a space therebetween for an electric heating element, said element being placed at a distance from the working end of said head, and thereafter pressing the metal plates beyond the limits of said heating element together to close said head at its working end.

In witness whereof, I hereunto subscribe my name this 6 day of June, A. D., 1923.

W. A. WHIPPLE.
